U.S. Cl. D26—14

FIG. 6.

FIG. 5.

FIG. 7.

FIG. 1 is a perspective view of a heater housing for hair for musical and other instruments showing our new design;

FIG. 2 is an enlarged side view of the extruded panel of FIG. 1;

FIG. 3 is a front elevation of a portion thereof;

FIG. 4 is a top plan view of a portion thereof;

FIG. 5 is a front perspective view of a modified embodiment of the extruded panel illustrated in FIG. 1, the broken lines indicating an audio amplifier housing which is shown for illustrative purposes only and does not form part of the claimed design;

FIG. 6 is a front elevation of the extruded panel of the modified embodiment of FIG. 5; and

FIG. 7 is a side view of the extruded panel illustrated in FIG. 5.

This is a continuation of design application serial No.

D.16,102 and design application Ser. No. D.16,103, both filed on Mar. 7, 1969 and now abandoned.

We claim:

The ornamental design for an extruded panel for musical and other instruments, as shown and described.
